CARBURETER.

1,041,481.

Specification of Letters Patent. Patented Oct. 15, 1912.

Application filed September 5, 1911. Serial No. 647,762.

To all whom it may concern:

Be it known that I, ELMER B. KALEY, a citizen of the United States, residing at Indianapolis, in the county of Marion and 5 State of Indiana, have invented a new and useful Carbureter, of which the following is a specification, reference being had to the accompanying drawings and to the letters and figures of reference marked thereon.

10 This invention relates to the type of carbureter that is employed for carbureting air by means of gasolene for use in internal combustion engines, the invention having reference more particularly to improved 15 means for feeding and atomizing the liquid hydro-carbon and mixing it with air.

15 The object of the invention is to provide an improved carbureter of simple construction that will be adapted to be produced at 20 relatively small cost, and be so constructed as to be highly efficient and economical in the use of the hydro-carbon in the explosive mixture; a further object being to provide a carbureter that will be so constructed that 25 the various parts thereof can be readily adjusted, or taken apart for the purpose of cleaning the apparatus; a still further object being to provide a carbureter that will be adapted to be repaired in case of 30 accidental damage thereto without discarding parts that may escape damage.

35 The invention consists in a carbureter of novel construction comprising primary feeding and atomizing apparatus, and adjustable detachable auxiliary feeding and atomizing apparatus; and the invention consists further in the novel parts, and the combinations and arrangements of parts, as 40 hereinafter particularly described and claimed.

45 Referring to the drawings, Figure 1 is a vertical central sectional view of the improved carbureter as preferably constructed; Fig. 2 a horizontal section on the line A A in Fig. 1; Fig. 3 a horizontal section on the line B B in Fig. 1 inverted, the float in the reservoir being omitted; Fig. 4 a section on the line C C in Fig. 1 omitting the fuel feed-valve and the float; Fig. 5 a 50 fragmentary section reproducing portions of Fig. 1 on an enlarged scale, and Fig. 6 a portion of Fig. 1 reproduced on an enlarged scale.

55 Similar reference characters in the various figures of the drawings indicate corre-

sponding elements or features of construction herein referred to.

A practical embodiment of the invention includes a reservoir which comprises a bottom 1 and a side wall 2, a valve-chest 3 being connected with the wall 2, and the wall has a suitable number of bosses 4, 5 and 6 thereon in which are ducts 7, 8 and 9 respectively, the bosses being suitably screw-threaded and two of them closed by means 60 of plugs 10 and 11 which may be removed if desired. The under side of the valve-chest 3 has a suitable extension 12 to which a fuel supply pipe may be connected. A duct 13 is formed in the bottom of the 65 valve-chest and a valve-seat 14 is formed at the upper end of the duct to be closed, or the extent of the opening in the duct to be varied by a valve 15 provided with an operating stem 16 extending up into a guide 17 70 inserted in the top of the valve-chest. A suitable lever 18 is mounted on a pivot 19 in the valve-chest and extends into the interior of the reservoir and has an annular float 20 secured thereon, the lever extending 75 beyond the pivot and having an end 21 suitably connected with the stem 16 so as to operate the inlet valve 15.

80 A cover 22 is provided which is seated upon the wall 2 of the reservoir and may be turned thereon to different positions, the cover preferably having a vent-hole 23 therein, or a vent may be otherwise provided if preferred. A section of mixing tube 24 is cast integrally with the cover 22 85 and is approximately U-shaped with its ends extending upwardly, an inlet end section 24' being connected to one end, and an outlet end section 24" being connected to the other end of the section 24. The lowermost portion of the mixing tube is central 90 on the cover 22 and a tube 25 is cast integrally on the central portion of the cover at the under side thereof, and it extends through the interior of the reservoir and 95 through the float and the bottom 1, the tube having a collar 26 formed thereon that is seated upon the bottom, the projecting end portion 27 of the tube having a nut 28 screwed onto it and against the under side 100 of the bottom. The middle and lower portion of the tube 25 is somewhat larger in diameter internally than the upper end portion, there being a tapering portion 29 somewhat below the upper end of the tube, 110

the upper portion 30 of the interior being the smaller in diameter and extending from the tapering portion to the mixing tube.

A feed tube 31 is supported uprightly in 5 the tube 25 by means of bridges 32 and 32', all cast integrally, the bridges having ducts 33 and 33' therein respectively that afford communication between the interior of the reservoir and the interior of the tube 31, the 10 upper end of the tube 31 having a spraying nozzle 34 thereon arranged with its orifice uppermost at a suitable distance below the entrance to the relatively smaller bore 30 of the tube 25. The tube 31 projects downward 15 below the end of the tube 25 and has external screw-threads 35 thereon to which a packing-nut 36 is connected, the tube 31 having also internal screw-threads 37. A valve-stem 38 is inserted through the packing-nut 20 and into the tube 31 and has screw-threads 39 thereon in contact with the screw-threads 37, the stem having a relatively smaller inner end portion 40 on the end of which is a needle-point valve 41 adapted to be seated 25 at the inner side of the orifice of the nozzle 34, for varying the area of the orifice and for assisting in atomizing the hydro-carbon, the tapering portion 29 and the relatively smaller portion 30 of the interior of the tube 30 assisting also in the atomizing operations, as does also the nozzle 34 as the air is drawn upward through the tube 25 and sucks the hydro-carbon past the valve 41 and out of the nozzle 34, the structure within the reservoir 35 constituting the primary feeding and atomizing or carbureting apparatus.

A valve-chest 42 is cast integrally with the mixing tube section 24' and has a bushing 43 screwed adjustably into the under side 40 thereof in a suitable opening, an air-inlet valve 44 being removably seated upon the upper or inner end of the bushing and provided with a guide stem 45 that is movable in a hollow guide 46 adjustably supported 45 in the top of the valve-chest, a spring 47 being seated upon the valve and against the inner end of the guide for normally holding the valve to its seat, the valve being adapted to be opened only at relatively high speeds 50 of the engine, as an auxiliary valve for admitting an increased supply of air or carbureted air to the mixing tube.

In order that the air admitted by the auxiliary air valve may be more highly carbureted than would be possible by means of the primary fuel feeding apparatus, a suitable valve-chest 48 is provided which has a tube 49 cast on one side thereof and adapted to be secured in either one of the bosses on 60 the side of the reservoir, the tube as illustrated being screwed into the boss 4, and as will be understood, in case the valve-chest 3 interferes with existing construction of the engine or other machinery, the reservoir 65 may be turned so as to move the valve-chest

out of the way and the cover 22 adjusted accordingly, and either one of the plugs 10 and 11 may be removed and the tube 49 inserted in its place, the boss 4 then being closed with a plug. The valve-chest 48 has 70 a packing-box 50 on its upper end in which is a packing-gland 51. A tube 52 is inserted through the gland and screwed adjustably into the valve-chest 48 beyond the bottom of the packing-box, the tube 52 having a spraying nozzle 53 on its upper end which preferably has sockets 54 therein to receive a suitable tool for turning the tube so as to raise or lower it. The upper portion of the tube 52 has external screw-threads 55 thereon on which a dish-shaped deflector 56 is adjustably screwed, so that it may be raised or lowered with respect to the nozzle and is prevented from accidental movement by means of a lock-nut 57 screwed onto the tube 80 against the deflector. The deflector is somewhat larger in diameter than the interior of the bushing 43 and is arranged at a suitable distance below the bushing. The lower portion of the valve-chest 48 has an extension 58 85 thereon which has screw threads 59 therein, a packing-nut 60 being placed on the end portion of the extension. A valve stem 61 is inserted through the packing-nut and has screw threads 62 thereon in contact with the screw threads 59, the valve stem extending up through the tube 52 and having a needle-point valve 63 on its upper end extending into the orifice of the nozzle 53, for varying the area of the orifice and coöperating with the nozzle to assist in atomizing the hydro-carbon which may be drawn from the reservoir by the higher velocity of the air entering the auxiliary air valve, the dish-shaped deflector serving to create partial vacuum at 90 the nozzle 53, so that the air passing between the deflector and the lower end of the bushing 43 when entering the bushing will the more effectually suck up the hydro-carbon, the valve 44 assisting also in atomizing the liquid as it passes with the air into the mixing tube. The outlet end 64 of the mixing tube section 24'' is suitably adapted to be connected with an explosive engine or a pipe leading thereto. The section 24'' has a rock shaft 65 mounted therein to which a butterfly valve 66 is secured, the shaft having an operating arm 67 thereon.

In practical use, while the engine is being started and when running at relatively 120 slow speed, the hydro-carbon which is maintained at the desired level in the reservoir by means of the float therein, approximately at the level of the top of the nozzle 34, is fed by means of the valve 41 and taken up and atomized in the tube 25 by means of the air passing through the tube into the mixing tube section 24 from which the carbureted air is drawn through the tube section 24'' into the engine cylinders. When 130

- the suction increases due to increasing speed of the engine, the auxiliary valve, 44 is brought into action and the air drawn in at higher velocity draws the hydro-carbon from the nozzle 53 as before explained, so that the auxiliary feeding is automatically brought into action as required by the engine, and its action discontinued automatically when the engine is again reduced in speed below the normal rate. It will be understood that the top of the nozzle 53 is slightly higher than the level of the top of the nozzle 34 so as to prevent leakage of the liquid when the auxiliary valve is not in action.
- Having thus described the invention; what is claimed as new is—
1. A carbureter including a reservoir, a mixing tube, an open-bottom air-valve-chest on the tube, a valve in the air-valve-chest, a fuel-feed valve-chest connected with the reservoir and provided on its top with an adjustable nozzle that is below the open bottom of the air-valve-chest, a dish-shaped deflector supported on the nozzle, and a valve in the nozzle.
  2. A carbureter including a reservoir, a mixing tube, an open-bottom air-valve-chest on the tube, a valve in the air-valve-chest, a fuel-feed valve-chest connected with the reservoir and provided on its top with a nozzle that is below the open bottom of the air-valve-chest, a dish-shaped deflector adjustably supported on the nozzle, and a valve in the nozzle.
  3. A carbureter including a reservoir, a mixing tube mounted on the reservoir, an auxiliary air-inlet valve at one end of the mixing tube, fuel-feeding and atomizing apparatus within the reservoir and connected with the mixing tube, and auxiliary fuel-feeding and atomizing apparatus mounted exteriorly to the reservoir in the atmospheric air below the auxiliary air-inlet valve and connected with the reservoir.
  4. A carbureter including a reservoir comprising a bottom and a side wall, a cover on the side wall, a mixing tube on the cover, an auxiliary air-inlet valve at one end of the tube, a primary air-inlet tube extending through the reservoir to the mixing tube, a fuel-feed valve in the primary air-inlet tube, a valve-chest having an inlet tube connected to the side wall of the reservoir, a spraying nozzle connected to the valve-chest and thereby supported below the auxiliary air-inlet valve, and a fuel-regulating valve in the nozzle.
  5. A carbureter including a reservoir having a plurality of bosses thereon provided with ducts, an inlet valve-chest on one side of the reservoir, a cover on the reservoir and rotatively adjustable thereon, a mixing tube fixed on the cover, a valve-chest on the tube beyond the exterior of the reservoir, a feed valve-chest having an inlet-tube removably inserted in one of the bosses and having a nozzle thereon, a valve adjustable in the nozzle, and plugs removably inserted in the remaining bosses.
  6. A carbureter including a reservoir, a mixing tube mounted on the reservoir and having an open bottom, a bushing adjustably connected with the open bottom of the mixing tube, fuel-feeding and atomizing apparatus within the reservoir and connected with the mixing tube, and auxiliary fuel-feeding and atomizing apparatus including a feed-valve and a nozzle and mounted exteriorly to and connected with the reservoir for discharging through the bushing into the mixing tube.

In testimony whereof, I affix my signature in presence of two witnesses.

ELMER B. KALEY.
